CLAIM

The ornamental design for the headlamp with band, as shown and described.

DESCRIPTION

FIG. 1 is an elevated isometric view of a first embodiment of a headlamp with band showing the new design;

FIG. 2 is a front view of the headlamp with band as shown in FIG. 1;

FIG. 3 is a rear view of the headlamp with band as shown in FIG. 1;

FIG. 4 is a left side view of the headlamp with band as shown in FIG. 1;

FIG. 5 is a right side view of the headlamp with band as shown in FIG. 1;

FIG. 6 is a top view of the headlamp with band as shown in FIG. 1;

FIG. 7 is a bottom view of the headlamp with band as shown in FIG. 1;

FIG. 8 is an elevated isometric view of a second embodiment of a headlamp with band showing the new design;

FIG. 9 front of the headlamp with band as shown in FIG. 8;

FIG. 10 is a rear view of the headlamp with band as shown in FIG. 8;

FIG. 11 is a left side view of the headlamp with band as shown in FIG. 8;

FIG. 12 is a right side view of the headlamp with band as shown in FIG. 8;

FIG. 13 is a top view of the headlamp with band as shown in FIG. 8; and,

FIG. 14 is a bottom view of the headlamp with band as shown in FIG. 8.

In the drawings, the broken lines depict portions of the headlamp with band in which the design is embodied and form no part of the claimed design.
